ELLIOTT I. PETERSEN, OF ENFIELD, CONNECTICUT, ASSIGNOR TO BIGELOW-SANFORD CARPET CO., INC., OF THOMPSONVILLE, CONNECTICUT, A CORPORATION OF MASSACHUSETTS

LABEL

REISSUED

Application filed November 2, 1931. Serial No. 572,490.

This invention relates to labels for rugs and carpets, and more particularly to a double label adapted to mark both the front and back of a rug or carpet.

It has been proposed heretofore to print or otherwise mark the back of a rug or carpet so as to display thereupon the name given the fabric, the name of the manufacturer and other desired information, but in order to 10 read this information it is necessary to turn the rug or carpet over or fold it back.

It is desirable at times to display similar information at the face of the rug or carpet without permanently marking the face thereof. For example, when rugs are on sale and piled one on top of the other, or otherwise displayed, it may be desirable to provide means for marking them so that the maker's name and other information can be easily 20 read at the upper face or edge of the rug, thus making it unnecessary to examine the back of the rug for this information.

Such marking means at the face of a rug would, however, be undesirable or unsightly 25 after the rug has been sold and placed in use. It is, therefore, important that the marking means at the face of the rug be readily removable after the rug is sold, but it should be so constructed and secured in place that it is 30 not likely to be accidentally torn off or injured prior to the sale of the rug.

The present invention, therefore, relates to a special form of label adapted to permanently mark the back of a fabric and to temporarily mark the face thereof and comprises a double label consisting of two parts, one of which is adapted to be permanently secured to the back of a rug or carpet, while the other is removably secured at the front 40 thereof, and a foldable connection is provided between the two labels to help retain the front label in place.

The arrangement is such that the front label is positioned adjacent an edge of the rug where it can be conveniently read by looking at the same either at the edge or upper face of the rug or carpet, and may be easily examined even when the rug to which it is secured is in a stack under other rugs. After 50 a rug having the double label of the present

invention secured thereto is sold, the front label may be readily removed by severing its connection with the rear label and pulling or cutting it loose from the means that attaches it to the front face of the rug. 55

The various features of the present invention will be more fully understood from the following description when read in connection with the accompanying drawings illustrating one good, practical form thereof. 60

In the drawings:—

Fig. 1 is a face view of the double label of the present invention;

Fig. 2 is a perspective view of the end portion of a rug looking at its upper face and 65 provided with the label of the present invention;

Fig. 3 is a sectional view taken on the line 3—3 of Fig. 2;

Fig. 4 is a perspective view of the portion 70 of the rug of Fig. 1, but shows the rug turned up to disclose the label upon the back thereof; and

Fig. 5 is a view similar to Fig. 4 but shows the label for the front of the rug removed. 75

The double label of the present invention may be used upon rugs, carpets, and other fabrics where it is desired to provide a permanent label at one face and a removable label at the opposite face, and may be secured at 80 either an end or selvage edge of the rug or other fabric to be marked.

In the embodiment of the invention illustrated the double label comprises an elongated strip of material and is provided at one 85 end with the front label 1 and at the other end with the back label 2, and the intermediate portion 3 of the elongated strip is adapted to be folded about the edge of a rug or other fabric. 90

The elongated strip used in forming the label may be constructed of various materials but since the rear label 2 is intended to remain permanently secured in place, it should be constructed of durable material and both 95 labels should present a pleasing appearance. The elongated strip may therefore be formed of woven silk or other textile material of any desired color, and the name of the manufacturer of the rug, its size, and trade-name, 100

trade-mark or other information may be printed or otherwise provided near the opposite ends of the elongated strip, as best shown in Fig. 1.

5. The manner in which the double label of the present invention may be attached to a rug, carpet or other fabric is illustrated in connection with the end portion of a rug having the usual backing fabric 4, pile upper 10 face 5 and end fringe 6, and in the rug construction shown the pile 5 is omitted from the ground fabric adjacent the fringe, as indicated by 7.

The double label comprising the parts 1, 2 15 and 3 is conveniently secured to the rug by sewing the end of the upper label 1 to the portion of the upper face of the fabric 7 from which the pile is omitted. This is a simple sewing machine operation, and the end of the 20 label is preferably turned under as at 8, and is secured to the backing fabric by the row of stitches 9. The intermediate portion 3 of the strip may then be looped loosely about the 25 fringe 6, as shown, so as not to injure the fringe and secured to the back of the fabric 4 by the row of stitches 10. The remaining end portion 2 of the fabric strip may be sewed to the back of the rug as at 11. In this manner the rear label 2 is firmly bound in a flat 30 condition to the back of the rug to permanently mark the same.

The front label 1, it should be noted, is held in place partly by the stitches 9 and partly by the looped intermediate section 3, the arrangement being such that the upper label 1 can be easily read from either the edge or 35 upper face of the rug, and is held in an extended condition and from being accidentally folded over against the face of the pile 5 by 40 the connection 3.

When a rug or carpet provided with the present double label is sold, the upper label 1 and intermediate portion 3 are readily removed by severing the label forming strip 45 along a line 12 adjacent to the row of stitches 10 and by cutting or breaking the row of stitches 9 at the face of the rug.

It will be seen from the foregoing that the 50 present label comprises a portion 2 permanently secured to the back of the fabric, a portion 1 removably secured to the face of the fabric, and an intermediate or looped portion 3 which is of sufficient size to clear the fringes 6 so as not to fold or crumple them. It will 55 also be understood that as a result of the present construction any desired information may be displayed in a pleasing manner at both the back and front of a rug, carpet or other fabric and that this is accomplished 60 without in any way permanently marking or injuring the face of the rug or other fabric.

What is claimed is:—

1. In combination with a floor covering, a 65 double label formed of sheet material and

comprising two end portions connected by a foldable intermediate portion, one end portion forming a back label permanently secured to the back of the floor covering, the other end portion forming a front label secured to and displayed at the upper edge of the floor covering while connected to the back label by said intermediate portion which is folded around the edge of the floor covering. 70

2. In combination with a floor covering, a 75 double label formed of textile material and comprising two end portions connected by a foldable intermediate portion, one end portion forming a back label permanently secured to the back of the floor covering, the 80 other end portion forming a front label secured to and displayed at the upper face of the floor covering, and retained in an extended position upon the floor covering through its connection to the back label by said intermediate portion which is folded around the edge of the floor covering and is adapted to be severed when the front label is removed.

3. In combination with a floor covering, a 85 double label formed of sheet material and comprising two end portions connected by a foldable intermediate portion, one end portion forming a back label firmly secured to and permanently displayed at the back of the floor covering, the other end portion forming a front label provided with information to be displayed at the face of the floor covering, said front label being retained in place by having one edge thereof secured against the upper face of the floor covering and by its 90 attachment to the back label through said intermediate portion that is folded around the edge of the floor covering. 95

4. In combination with a floor covering, a 100 double label formed of sheet material and comprising two end portions connected by a foldable intermediate portion, one end portion forming a back label firmly secured to and permanently displayed at the back of the floor covering, the other end portion forming a front label provided with information to be displayed at the upper edge of the floor covering, said front label having an edge 105 thereof secured to the upper face of the floor covering and attached to the back label through said intermediate portion that is folded around the edge of the floor covering, and the front label being removable after severing said intermediate portion near the back label. 110

5. In combination with a floor covering, a 115 double label formed of a strip of woven fabric having one end portion printed or marked to form a back label permanently sewed to the back of the floor covering and having 120 its other end portion printed or marked to form a front label displayed at the front edge of the floor covering, and a line of stitches 125 securing the front label at the front of the floor covering, the remaining portion of the 130

front label being connected to the back label by an intermediate portion of the fabric strip that is looped about the edge of the floor covering.

5 In testimony whereof, I have signed my name to this specification.

ELLIOTT I. PETERSEN.
